UNITED STATES PATENT OFFICE.

JOHN BRAYTON HARLOW, OF NEW YORK, N. Y., ASSIGNEE, BY MESNE ASSIGNMENTS,
TO WESTERN ELECTRIC COMPANY, INCORPORATED, A CORPORATION OF NEW YORK.

SELECTIVE SIGNALING SYSTEM.

1,210,642.

Specification of Letters Patent. Patented Jan. 2, 1917.

Application filed May 6, 1915. Serial No. 26,253.

To all whom it may concern:

Be it known that I, JOHN BRAYTON HARLOW, a citizen of the United States, residing at New York, in the county of New York and State of New York, have invented 5 certain new and useful Improvements in Selective Signaling Systems, of which the following is a full, clear, concise, and exact description.

This invention relates to signaling means 10 for railway systems and has for its object to provide signaling means for a single track railway system, whereby an operator or a despatcher at a distant station may at 15 any time cause the operation of signals to indicate to him the presence of a train in, or the absence of a train from, any particular section of railway track and the direction of movement of a train in a particular 20 section.

In accordance with the general features 25 of this invention a single track railway is divided into sections, each section having associated with it a selectively controlled answer-back mechanism adapted to give a plurality of different indications, together with an answer-back circuit, and switching means controlled by the presence of a train in a section and its direction of movement to 30 cause said answer-back mechanism to send over said answer-back circuit a signal indicative of these facts. The switching mechanism is conditioned when no train is in the section to cause the answer-back mechanism 35 to give over said answer-back circuit a signal indicating the absence of a train from the section when the selective means is operated.

The drawing is a diagram of a circuit and apparatus embodying the features of this invention.

In the drawing, 5 designates a section of single track railway which is insulated from adjacent sections 6 and 7 in the usual manner. A pair of power leads 8 and 9 supplied 40 with alternating current extend parallel to the track and have connected with them transformer primaries 10, 11 and 12, said transformer primaries being located at the opposite ends and at the center of each section. Connected with the opposite rails at 45 each end of the section 5 are track relays or magnets 13 and 14 which are normally energized over the rails from current supplied by a transformer secondary 15 in inductive 50 relation to the transformer primary 11.

Located at each track section is an answer-back means comprising a motor 20 and a plurality of coded interrupters 21, 22 and 23, each adapted to give a signal different from the others. The operation of the answer-back means is controlled by a selectively operated device 24. The selectively operated device 24 is connected with line wires 25 and 26 and controlled from a despatcher's station 27 supplied with an impulse relay 28 and a transmitter 29 therefor. Bridged across the line wires 25 and 26 at the despatcher's station is a telephone receiver 30 adapted to receive signals from the answer-back means at the track section. 60 Switching means comprising electromagnets 31, 32, 33 and 34 are conditioned by the presence of a train in the section, or by its absence therefrom, to include one or the other of the interrupters 21, 22 and 23 in an answer-back circuit extending to the despatcher's station after the operation of the selectively operated device 24.

In the operation of the system, the despatcher desiring to secure a signal indicative of the condition of track section 5 will operate his transmitter 29 to cause the selective device 24 to close contacts 40 and 41. The closure of these contacts 40 and 41 completes an energizing circuit for relays 42 and 43 over the line wires 25 and 26 and causes them to close contacts 44 and 45 and 46. Assuming now that there is a train 75 in the section traveling in the direction indicated by the arrow. In this case, the track magnet 13 will be deenergized and will have opened contact 50 controlled thereby. The opening of the contact 50 will open the circuit of the relay 33 which may be traced from a common conductor 51 over conductor 52, through winding of relay 33, over conductor 53 and through contact 50 to the opposite side of the induction coil secondary 54. The deenergization of relay 33 closes contacts 55 and 56 and opens contact 57. 80 The closure of contact 55 completes an energizing circuit for relay 32 from the transformer secondary 58, causing said relay to pull up its armatures and close contacts 65 and 66 and open contacts 67 and 68. The closure of contact 66 completes a circuit which includes contacts 69 and 70 of the answer-back interrupter 23 in an answer-back circuit which may be traced from line 85 wire 26 through condenser 71, contact 45, 110

armature of motor 20, contacts 69 and 70, contact 66, conductors 72, contact 46 and condenser 75 to line wire 25. The closure of contact 44 by the operation of relay 42 completed an operating circuit from the transformer secondary 58 for the motor 20, so that the inclusion of the interrupter 23 in the circuit above traced will cause a coded signal to be sent over the line wires 25 and 26 which will be audible in the receiver 30, and which will notify the dispatcher that there is a train in block 5 moving in the direction of the arrow. This answer-back circuit will be conditioned for operation by the actuation of the selectively operated means 24 so long as the train is in the section, although the energizing circuit for the relay 32 may be shifted from the contact 55 of relay 33 to contact 76 of relay 31. This is brought about by reason of the fact that as the train moves along the track section 5 the potential of the track rails within this section will shift, gradually strengthening toward the end from which the train entered and gradually weakening toward the end which the train is approaching. As the train approaches, the transformer secondary 15 will shunt sufficient current from the track magnet 14 to cause it to release and open contact 77. This will open the circuit of relay 31 causing it to release its armatures and close contacts 76 and 78. This will complete an energizing circuit for the relay 32 from the transformer secondary 58 through the contact 76 which will be in substitute of the path over which it was originally energized, which circuit may be traced from transformer secondary 58 over conductors 52 and 51 through a normally closed contact of relay 34, winding of relay 32, contacts 76 and 65, back to the transformer secondary, so that by the time the train has reached a position in the section 5 which will permit sufficient current to flow through the track relay 13 to energize it and complete the energizing circuit for the relay 33, there will be no danger of the relay 32 becoming deenergized.

Had the train been coming from the opposite direction to that shown and described, it would have brought the interrupter 21 with contacts 80 and 81 into the answer-back circuit through the deenergization of track magnet 14, and relay 31 and the energization of relay 34—this operation being precisely the same as that previously described for completing the answer-back circuit for interrupter 23.

Should it happen that there is no train in the track when the selectively operated device 24 is set to close contacts 40 and 41, then both track magnets 13 and 14 will be energized, as will also relays 31 and 33, while the circuits of relays 32 and 34 will be open, thus closing contacts 68 and 82 and completing a circuit for including the

contacts of 83 and 84 of interrupter 22 in the answer-back circuit and the dispatcher will receive a tone in the receiver 30 in accordance with the code of interrupter 22, and will know that section 5 is unoccupied. 70

What is claimed is:

1. In a signaling system for single track railways, a railway track divided into sections, an answer-back mechanism individual to each section including a plurality of interrupters, selectively operated means for controlling the operation of said answer-back mechanism, an answer-back circuit completed by the operation of said selectively operated means, and switching means conditioned by the presence of a train in the section and its direction of movement to include in said answer-back circuit one of two of the interrupters and by the absence of a train from the section to include a third one of said interrupters in said answer-back circuit. 80

2. In a signaling system for single track railways, a railway track divided into sections, an answer-back mechanism associated with each of said sections for producing a plurality of characteristic signals when operated, selectively operated means for controlling the operation of said answer-back mechanism, an answer-back circuit completed by the operation of said selectively operated means, and switching means controlled from said track to cause said answer-back mechanism to send over said answer-back circuit one or another of the signals depending upon the position and direction of movement of a train with respect to a particular section. 90

3. In a signaling system for single track railways, a railway track divided into sections, an answer-back mechanism individual to each section including a plurality of interrupters, selectively operated means for controlling the operation of said answer-back mechanism, an answer-back circuit completed by the operation of said selectively operated means, a track relay located at each end of each section, the track relay at one end of said section being operated by the entrance of a train in said section traveling in one direction and that at the other end of said section being operated by the entrance of a train in said section traveling in the opposite direction, and switching means separately controlled by the operation of said relays to include in said answer-back circuit one or the other of two interrupters of the answer-back mechanism, whereby an answer-back signal designating the position and direction of movement of a train may be obtained. 110

4. In a signaling system for single track railways, a railway track divided into sections, an answer-back mechanism individual to each of said sections and provided with 120

- interrupters, each adapted to give a signal different from the others, selectively operated means for controlling the operation of said answer-back mechanism, an answer-back circuit closed by the operation of said selectively operated means, a normally energized track magnet at each end of each of said sections adapted to be deenergized by the passage of a train through said section, 5 switching means controlled by the track magnet first deenergized to connect one of said interrupters in said answer-back circuit and means for preventing the deenergization of the second magnet in response to 10 the passing of the same train from connecting another of said interrupters in said answer-back circuit.
5. In a signaling system for single track railways, a single track railway divided into sections, an answer-back mechanism individual to each of said sections and provided with three interrupters, each adapted to give a signal different from the others, selectively operated means for controlling the operation 15 of said answer-back mechanism, an answer-back circuit closed by the operation of said selectively operated means, switching means conditioned by the entrance into a section by a train from one direction to connect one of 20 said interrupters in said answer-back circuit, by the entrance of a train into said section from an opposite direction to connect another of said interrupters in said answer-back circuit and by the absence of 25 a train from said section to connect the third 30 one of said interrupters in said answer-back circuit.
6. In a signaling system for single track railways, a railway track divided into sections, an answer-back mechanism associated with each of the sections for producing a plurality of characteristic signals when operated, selectively operated means for controlling the operation of said answer-back mechanism, an answer-back circuit completed by the operation of said selectively operated means, and switching means controlled from said track to cause said answer-back mechanism to send over said answer-back circuit one or the other of the signals, depending upon the direction of movement of a train in the particular section. 35
7. In a signaling system for single track railways, a railway track divided into sections, an answer-back mechanism individual to each section and including a plurality of codifying devices, selectively operated means for controlling the operation of the answer-back mechanism, an answer-back circuit completed by the operation of the selectively operated means, and switching means controlled from the track and depending upon the direction of movement of a train in the particular section for operatively associating one of the codifying devices and the answer-back mechanism for sending over the answer-back circuit a characteristic signal. 40 45 50 55 60 65

In witness whereof, I hereunto subscribe my name this 4th day of May, A. D. 1915.

JOHN BRAYTON HARLOW.
